[57] CLAIM

The ornamental design for a reader for image information storing/retrieving machine, substantially as shown and described.

DESCRIPTION

FIG. 1 is front, top and right side perspective view of a reader for image information storing/retrieving machine showing our new design;

FIG. 2 is a front elevational view thereof;

FIG. 3 is a right side elevational view thereof, the opposite side being a mirror image;

FIG. 4 is a top plan view thereof; and

FIG. 5 is a rear elevational view thereof.

FIG. 1

FIG. 2

FIG. 3

FIG. 4

FIG. 5
